Primary Examiner — Steven J Czyz*Assistant Examiner* — Varun Salil Kamat(74) *Attorney, Agent, or Firm* — Banner & Witcoff, Ltd.(57) **CLAIM**

The ornamental design for a furniture nook, as shown and described.

DESCRIPTION

FIG. 1 is a top, front, right perspective view of a furniture nook showing our new design;

FIG. 2 is a front view thereof;

FIG. 3 is a rear view thereof;

FIG. 4 is a left side view thereof;

FIG. 5 is a right side view thereof; and,

FIG. 6 is a top view thereof.

The broken lines depicting the remainder of the furniture nook form no part of the claimed design.

1 Claim, 6 Drawing Sheets(56)
